UNITED STATES PATENT OFFICE.

CHARLES E. EMERY, OF BROOKLYN, NEW YORK.

WORKING-BEAM.

SPECIFICATION forming part of Letters Patent No. 398,955, dated March 5, 1889.

Application filed June 6, 1888. Serial No. 276,276. (No model.)

To all whom it may concern:

Be it known that I, CHARLES E. EMERY, a citizen of the United States, residing in the city of Brooklyn, county of Kings, and State 5 of New York, (office New York city,) have invented certain new and useful Improvements in the Working-Beams of Steam-Engines; and I do hereby declare that the following is a full, clear, and exact description of the 10 same, reference being had to the accompanying drawings, making part of this specification, in which—

Figure 1 is a vertical elevation of the working-beam as improved, and Fig. 2 a plan view 15 of the strap of the beam for the greater portion of its length. Fig. 3 is a vertical elevation of the greater part of the length of a modified form of the improved working-beam, and Fig. 4 is a plan view of the strap of the 20 same for the greater portion of its length.

A is the web of the beam, provided with long arms A' A' and short arms A² A². B is the beam-strap, composed of a number of layers or sections, b b b. C' and C⁵ indicate 25 plate-clamps; C³, strap-clamps; C³, intermediate plate-clamps, and C⁴ bolt-clamps. D is the main center. E E are openings for the main connecting-pins. F F are openings for pins to connect to pumps, &c. G G, &c., are 30 keys for tightening the compound strap over the web. The elevation, Fig. 1, shows the general form of the beam of the typical American beam-engine. The beam is constructed with a cast-iron web, A, in the general form 35 of a cross with horizontal arms A' A', longer than the vertical ones, A² A², which web is surrounded by a heavy lozenge-shaped strap of wrought-iron, into which the web is keyed. At the longer angles of the lozenge pin-holes 40 are provided for the main connections, which are formed in the strap in Figs. 1 and 2, and in the web in Figs. 3 and 4. The web of the beam is provided with openings for the main center pin and for connections to pumps, &c.

45 A beam-strap is ordinarily made in one large forging, "built up," as it is called, by welding together many pieces. A forging of this kind is deficient in strength, homogeneity, and extensibility as compared with smaller 50 bars of rolled iron. Such beam-straps have

broken in many cases, causing the wreck of the principal parts of the engine and much of the surrounding wood-work, also, not unfrequently, loss of life.

In my improved beam the beam-strap is 55 divided longitudinally into a number of parts, each resembling in elevation the shape of beam-straps of former construction; but the total thickness of the strap being made up of a number of comparatively thin sections each 60 can be better and more uniformly worked in the operation of forging, and can be made much stronger per unit of section and more reliable, for reasons well known by those skilled in the art. The several parts are laid closely 65 together, fitted as a unit over the arms of the web A, and secured to the same by keys G G in substantially the same way as when the strap is made of one piece. Thus connected the several parts will act together in tension 70 as a unit, the same as if they had been forged together; but in compression their full strength cannot be utilized unless they are prevented from buckling. This is accomplished by clamping them together by means 75 of clamps of different forms adapted to the portion of the compound strap operated upon. At the ends it is proposed to use plate-clamps C⁵ C⁵, secured together by bolts passing through the joint (enlarged as necessary) between the web and the compound strap. At the half-length of the beam-strap clamps C³ C³ are employed. At the quarter-points arms on the web are fitted against the compound strap, and plate-clamps C³ C³, with holes for 85 two or more bolts and for a key, are clamped by the bolts to the compound strap at the same time that the keys are driven, to draw the strap tightly against the arms on the web and prevent shake. To accomplish this the 90 inner bolts adjoining the keys are made loose in the holes in web, so that the key draws the outer bolts tightly against the strap.

At points where the strap is clear of the web plain clamps C' C' are employed, consisting of two plates on opposite sides of the compound beam-strap, held tightly together by bolts. U-bolts may also be used with one plate to accomplish the same purpose. The strap at such points may or may not be swelled 95 100

out to receive the bolt-holes. Bolts forming bolt-clamps C⁴ C⁴ may be put through the compound beam-strap to clamp the parts together, if desired, the metal bars being swelled 5 opposite the holes to keep up the strength; or rivets may be used in a similar manner. When the end pins are put in the ends of the web, as in Figs. 3 and 4, the compound strap must be secured over it with keys well fitted 10 laterally in key-seats in the strap and web, the laminae of the latter being widened opposite the same to keep up the strength. The short arms of the web may be similarly secured, or saddles K K interposed, with wedges 15 G' G' between them and the ends of the arms, as shown, or the same construction may be adopted as is shown in Fig. 1. In the general way described a beam may be constructed of much greater strength than is possible 20 when the strap is made of a single piece. Moreover, a defect in one portion will rarely cause breakage of the whole, and if the factor of safety be made sufficiently large one

part may break and the others continue to do the work until the difficulty is discovered and 25 remedied.

What I claim as my invention, and desire to secure by Letters Patent, is—

1. In combination with the web of a working-beam, a beam-strap composed of a number of thicknesses connected and operating together, substantially as and for the purposes specified.

2. In a working-beam, a strap composed of a number of laminae clamped together to act 35 as a unit, substantially as described.

3. The combination, with the web of a working-beam and a compound beam-strap formed of a number of thicknesses, of clamps for insuring the stability of the strap under compressive strains.

CHAS. E. EMERY.
